Morris L. Duskin, Chicago, Ill.

Application April 6, 1945, Serial No. 118,883

Term of patent 14 years

(Cl. D87—5)

To all whom it may concern:

Be it known that I, Morris L. Duskin, a citizen of the United States and a resident of the city of Chicago, in the county of Cook and State of Illinois, have invented a new, original, and ornamental Design for a Luggage Cover or Similar Article, of which the following is a specification, reference being had to the accompanying drawing, forming a part thereof.

On the drawing:

I claim:

The ornamental design for a luggage cover or similar article, as shown.

MORRIS L. DUSKIN.
